Attorney

UNITED STATES PATENT OFFICE.

CHARLES W. MEYER, OF NEAR JONESBORO, TEXAS.

BINDER REEL.

Application filed May 27, 1926. Serial No. 112,080.

This invention relates to binder reels and more particularly to a binder reel so constructed that the number of grain engaging slats thereof may be conveniently changed.

5 Grain binders as at present constructed are incapable of any considerable range of adjustment as to the slats thereof, providing only for reduction of the number of slats by removal of certain thereof. I have 10 found that in order to cause the grain to lay properly to the knife in different stands, it is necessary that very close regulation of the number of slats employed be provided. In some instances, where the grain is very 15 short and heavy, a proper cut can only be obtained by the use of ten slats upon the reel. In other stands, where the grain is tall and very light, but three slats may be required upon the reel and accordingly between 20 these two limits, it is desirous that any number of slats may be employed. It is, of course, desirous that regardless of the number of slats, these slats be as nearly as possible uniformly distributed. According- 25 ly, a more specific object of this invention is the provision of a grain binder reel upon which three, four, five, six, eight or ten slats may be employed and these slats uniformly distributed about the periphery of the reel. 30 A further object of the invention is to provide a device of this character which may be very readily and cheaply produced, which will be durable and efficient in service and a general improvement in the art.

35 These and other objects I attain by the construction shown in the accompanying drawings, wherein for the purpose of illustration is shown a preferred embodiment of my invention and wherein:—

40 Figure 1 is an inner face view of a reel hub for grain binders constructed in accordance with my invention, four slat arms being shown therein in solid lines, five slat arms being indicated in dotted lines in their 45 respective positions;

Figure 2 is a transverse sectional view therethrough on the line 2—2 of Figure 1;

Figure 3 is an outer face view of the shaft engaging portion of the hub;

50 Figure 4 is a section on the line 4—4 of Figure 1.

Referring now more particularly to the drawings, the numeral 10 generally designates a reel shaft engaging member which

55 may have any suitable means for clamping the same thereto. In the present instance,

the shaft 11 is shown as provided with a key 12 and the member 10 with a keyway for the reception of this key. The member 10 is further split, as at 13, and provided with clamping ears 14 whereby it may be drawn together to bind upon the same and prevent any longitudinal movement of the member 10. The shaft engaging member 10 is provided with a flange 15 to which the 60 reel arm supports 16 may be secured. In accordance with my invention, adjacent the member 10, this flange is formed with a series of openings 17, each adapted to receive a bolt or similar securing element 18 65 directed through an opening formed in the inner end of a slat arm 16.

Adjacent its periphery, the flange 15 is provided with a second series of openings 19, preferably arranged in pairs and having 70 the openings of each pair similarly spaced at opposite sides of a radius from the axis of the flange 15 drawn through one of the openings of the series 17. These pairs of openings are to receive securing elements 75 20 directed through openings formed in ears 21 upon the ends of the arms of U-shaped members 22 which straddle the associated arm 16 to clamp the same to the flange 15. The arms 16 will, of course, be secured to 80 one face of the flange 15 and upon the opposite face thereof, I preferably provide radial lines 23, each intersecting one opening 17 and extending between the pairs of openings 19. Each of these lines is num- 85 bered to designate whether the associated opening 17 and pair of openings 19 are to be employed when a given number of slats are to be applied to the reel. For example, 90 one of these lines may have associated therewith the numbers 10, 8, 6, 5, 4 and 3 indicating that the openings 17 and 19 which are 95 associated with the radial lines are to be employed to secure an arm 16 in position if any of these numbers represents the number of slats which are to be provided upon 100 the complete reel. An adjacent line may have thereon a single number as 10 indicating that the associated openings are to be employed only when ten slats are to be 105 placed upon the reel. It will be obvious that the arms may be very readily applied to the reel and that no difficulty will be experienced in so arranging the arms that the slats 110 are uniformly spaced.

It will, of course, be understood that the particular hub and flange construction illus-

trated are intended solely as illustration, as the invention is capable of application to the reel hubs of binders of different makes, in some of which the flanges are at right angles to the hubs and in others of which the flanges are at more less of an acute angle thereto. Furthermore, these flanges may be either formed integrally with the hub, as herein illustrated, or may be attached there-
to. It will be noted that a reel hub of this construction provides a much better support for the slat arms than that provided by the ordinary reel hub.

Since the invention is capable of other changes without in any manner departing from the spirit of my invention, I do not limit myself to the specific structure hereinbefore set forth except as hereinafter claimed.

I claim:—

1. A binder reel structure comprising a sleeve adapted to receive a shaft, means for clamping the sleeve upon the shaft, the sleeve being provided at one end with a flange disposed in a plane substantially at a right angle to the axis of the sleeve, said flange being provided with bolt openings arranged

in pairs, the members of the pairs of openings being located at diametrically opposite sides of the sleeve, and graduation characters provided upon the face of the flange adjacent the respective pairs of openings.

2. A binder reel structure comprising a sleeve adapted to receive a shaft, means for clamping the sleeve in position upon the shaft, said sleeve being provided at one end with a flange lying in a plane disposed substantially at a right angle to the axis of the sleeve, said flange being provided with several pairs of bolt openings, the members of the pairs of bolt openings being located at diametrically opposite sides of the sleeve and lines provided upon the face of the flange and disposed radially with relation to the sleeve and leading approximately toward the respective bolt openings and graduation characters provided upon the flange at said radially disposed lines and adjacent the members of the respective pairs of bolt open-
ings.

In testimony whereof I hereunto affix my signature.

CHARLES W. MEYER.
